SCREW-HOLDING SCREW DRIVER

John Hagness, Los Angeles, Calif., assignor to
Russell W. Edwards, Los Angeles, Calif.

Application January 21, 1941, Serial No. 375,170

1 Claim. (Cl. 145—50)

This invention relates to tools and more especially to a screw holding screw driver.

An object of the invention is to provide a simple, practical and inexpensive tool of the character described.

Another object of the invention is to provide a screw driver capable of holding a screw preliminary to and during the screw tightening process.

Other objects and advantages will appear and be brought out more fully in the following specification, reference being had to the accompanying drawing, wherein

Fig. 1 is a view, partly in section, showing an embodiment of my invention.

Fig. 2 is a sectional view taken along the line 2—2 of Fig. 1.

Fig. 3 is a view similar to Fig. 2 showing the tool in operative position.

Fig. 4 is a sectional view taken along the line 4—4 of Fig. 1.

Fig. 5 is a sectional view taken along the line 5—5 of Fig. 3.

Fig. 6 is a perspective view of the cam member.

Fig. 7 is a perspective view of a wedge pin member 15.

Referring more particularly to the drawing, I show a screw driver having a tubular handle portion 10 in which is positioned the end of a shank 11. Shank 11 has a flattened portion 12 providing abutments for a set screw 13 secured in handle portion 10. Shank 10 has the usual screw engaging point 14 and a bore 15 in which is rotatably positioned a wedge pin member 16.

Shank 11 has a recess 17 adapted to receive a collar 18 which is suitably secured to member 16 so as to prevent slidable movement of member 16 in bore 15. Member 16 has a tip 19 which is flattened on opposite sides and substantially of the same thickness as tip 14, however of greater length than its thickness, so as to engage the

sides of a screw slot when turned at right angles thereto; as clearly seen in the figures. A tubular cam member 20 is secured as by pin 21 in the upper end of handle portion 10 and has a cam slot 22 which engages the end portion 23 of member 16, which is formed at right angles to the axis of the tool as shown. The handle portion 10 may be provided with any suitable end construction such as a cap 24, as desired.

The operation of the invention will be clear from the foregoing description. The tool is placed with bit 14 in a screw slot as shown in Fig. 2 with shank 11 extended, and when shank 11 is retracted by pressure on end 24 to the position shown in Fig. 3, end portion 23 will be caused to move in cam slot 22 and turned 90 degrees. This will cause tip 19 to turn crosswise in the screw slot, Fig. 5, and wedge in the same and thus the screw will be tightly held while it is being started in a screw hole. When handle portion 10 is retracted, the reverse movement with respect to shank 11 will cause tip 19 to turn parallel to tip 14 and release the engagement with the screw slot.

Having described my invention, what I claim is:

A tool as described comprising a tubular handle, a tubular shank axially slidable but non-rotatably mounted in said handle and having a screw slot engaging tip portion, a wedge pin member rotatably but non-slidably mounted in the bore of said shank and having a wedge tip portion co-terminal with said shank tip portion, and means to rotate said member substantially 90 degrees when said handle is moved with respect to said shank by pressure applied to said handle, said means comprising a cam groove in the bore of said handle and a lateral projection on said pin member adapted to engage said cam groove.

JOHN HAGNESS.
